UNITED STATES PATENT OFFICE.

WILLIAM W. BLAKELY, OF DEXTER, MICHIGAN.

WHEEL BLOCK.

Application filed November 17, 1924. Serial No. 750,443.

This invention relates to wheel blocks such as are used to prevent movement of the wheels of vehicles when being shipped.

It is the object of the invention to provide a durable wheel block of simple and economical construction.

Another object is to provide a wheel block that may be easily secured to the floor of the conveyance after being positioned.

10 Other objects in the construction will appear in the description and the drawings.

Figure 1 is a perspective view of my invention taken from the front.

Figure 2 is a perspective view taken from 15 the rear showing a fragment of a wheel in dotted lines applied thereto.

In the views my wheel block is shown to be preferably formed from one continuous piece of sheet metal.

20 The reference numeral 1 designates a sheet metal plate which is integral with a sheet metal base 2 and a sheet metal brace 4. The plate 1 is upwardly and inwardly inclined from said base 2 at an angle suitable for engagement with a vehicle wheel 3 supported by a floor. Supporting the upper end of said plate and inclined to the base 2 in a reverse direction is the sheet metal brace 4.

30 Plate 1 is dished as shown at 5 to receive the tire of the engaged wheel while the marginal edges of said plate are bent downwardly as at 6 to give it strength and to prevent injury to the tires by having the edges exposed. The lower end of said plate 1 is bent under to form the base 2 of the wheel block. Ribs or corrugations 7, 8, and 9 are formed crosswise on said base while ribs 10 and 11 are formed lengthwise between the lateral ribs 7 and 9 for reinforcing purposes.

35 The upper end of said plate 1 is bent downwardly to form the brace 4 which is composed of the portions 12 and 13. The portion 12 is connected with the upper end of said plate 1 and bent downwardly in the same general direction, as said plate, while the portion 13 is a continuation of the portion 12 but is bent downwardly in a reverse direction to said plate 1. To reinforce said brace 4, longitudinal ribs 14 and 15 are formed on said portion 12 and longitudinal ribs 16 and 17 are formed on said portion

13 while the inwardly inclined ribs 18 and 19 are formed at the lower end of said portion 13. Said brace 4 is seated at its lower end on the base 2 between the longitudinal ribs 10 and 11 and the transverse rib 9, and is adapted to be held in engagement with said base by bearing against the rib 9 of the base when the weight of the vehicle wheel is being supported.

The brace 4 may be secured by welding or the like at its juncture with the base, if desired, but by reason of the bearing engagement this is not necessary.

The rearwardly extending end of said base 2 beyond the rib 9 forms a heel 20 having a plurality of holes 21 to receive nails or the like 22 for securing said block to the floor.

45 A retainer plate 23 is situated across the base 2 at the rear of the rib 8 for securing the base to the floor and for preventing the sliding and skewing of the block. This is accomplished by having holes 24 in each end of said cross member 23 through which nails or the like such as 25 are driven to secure the same to the floor. It is preferable to have the inner hole on each end of the 50 retainer plate 23 register with a hole (not shown) through the base 2 so that when nailed the base 2 will be directly secured.

55 It will be seen that when the wheel is in engagement with the block, it tends to slide 85 the block rearwardly which is prevented by the rib 8 bearing against the cross member 23.

60 It will be noted that there are a plurality of holes 26 in the base to provide further 90 means for securing the block to the floor if deemed necessary.

65 What I claim as my invention is:

1. A wheel block formed of a single sheet of metal having a base portion provided with 95 an upstanding projection, an upwardly inclined wheel engaging portion, and a downwardly inclined brace portion having the lower end thereof engaging the base portion and upstanding projection.

100 2. A wheel block formed from a single sheet of metal having a base portion, an upwardly inclined wheel engaging portion, and a downwardly inclined brace portion, said brace portion having a free end resting on 105 the base and a projection on the base in

rear of the brace member constituting a stop therefor.

3. A wheel block having a base portion, a wheel engaging portion projecting upwardly from the base portion, a base projecting downwardly from the upper end of the wheel engaging portion freely engaging

the base portion, reinforcing ribs on said base portion and brace, and means for securing said base portion upon the support 10 including a retainer plate extending transversely of the base portion.

In testimony whereof I affix my signature.

WILLIAM W. BLAKELY.
